UNITED STATES PATENT OFFICE.

ARO M. HARVEY, OF KANSAS CITY, MISSOURI.

PRESS BOARD.

Application filed November 22, 1926. Serial No. 149,928.

My invention relates to devices for the carrying of fabric articles during the pressing of the same, and more particularly to pressing boards used in laundries and dry-cleaning establishments. It is my purpose to provide a pressing board unit having a plurality of board members and so being adapted for the efficient handling of a variety of articles to be pressed, especially for the finishing of sleeves of different apparel items.

In accomplishing this purpose I provide a bracket which is preferably supported on a gooseneck vertical pedestal and is provided with a laterally extended sole; and a plurality of pressing boards representing the several shapes and sizes which the industry and the particular dry cleaner may desire for the efficient and expeditious pressing of articles of various sizes and shapes. I particularly offer novel means of attaching a pressing board to the bracket so that a board may be removed quickly and easily, and a different board may be attached, by a minimum of movements; the board fitting snugly on the sole of the bracket and being firmly secured thereto, whereby the operation of pressing upon it may be carried on most successfully.

The provision of a plurality of boards makes it possible for the owner of an establishment to install a substantial pedestal and bracket, and provide a desired number of different shapes of pressing boards, at a minimum of expense and storage room; as contrasted with the present situation in which the more satisfactory available boards or devices must be separately set up and so occupy a comparatively large amount of work-room space, or must be moved into position from storage when required; or a single board ill-adapted to the many sorts of articles pressed upon it must be installed. The several features of my invention and their functions will be more particularly described with references to the drawings, in which:

Fig. 1 is a perspective view of my pressing board device.

Fig. 2 is a longitudinal sectional view, the base and pressing board members being shown in part.

Fig. 3 is a perspective view of the supporting member of the pressing board and of the bracket, disconnected. 55

Fig. 4 is a perspective view of the pressing board and its supporting member.

Fig. 5 is a sectional view of a part of the bracket containing the means of latching the pressing board to the bracket. 60

Fig. 6 is a vertical transverse section of the pressing board and its supporting member.

Referring more in detail to the drawings:

1 designates a bracket comprising a base plate 2, a pedestal or support 3 and a sole or plate 4, the bracket being preferably a casting, the base plate, pedestal and sole being integral. The sole is preferably of flatiron shape and the broader portion thereof is fixed to the pedestal, the narrower end thereof being extended laterally and relatively parallel with the base plate. The pedestal is preferably curved over the base plate and gooseneck shaped and has a rearwardly extending rib 3' provided with a boss 3''; the combination of the gooseneck-shaped pedestal and the extended sole providing the usual form of a pressing device for convenient manipulation thereon of garments. 70 The sole is provided with a central longitudinal surface rib 5 (Fig. 3) which declines towards the edges. The sole is provided, on a position preferably adjacent the juncture of sole with pedestal, with a tapering opening constituting a socket 6; and has a longitudinal bore 7 extending from the fixed end of the sole, and parallel with its axis, to said socket. 80

The outline of the bore 7 in the sole is disclosed in Fig. 5 wherein shoulders 8 are shown constituting a restricted opening for said bore into the tapering socket 6. A locking element is provided preferably a ball 9 movable in the bore 7 and projectible into the socket 6 and restrained from egress into the socket by the shoulders 8. A spring 10 is positioned in the bore bearing against the ball and against a dowel 11 mounted in said bore and fixed therein by a pin or screw indicated by 12 projected through the sole adjacent the fixed end thereof and into an aperture 13 of the dowel. The spring serves to hold the ball partly projected into socket 6. 95 100

and in contact with the shoulder 8; and to return the ball to such engagement upon the release of any influence that may have displaced it therefrom.

5 The dowel projects from the fixed end of the sole to an extent measured by adaptation of the dowel's end curves for engagement of the dowel with a pressing board supporting member 14, and detachment therefrom of the 10 supporting member by a tilting motion, as will now be described.

The supporting or attaching member 14 comprises a plate 15, the under surface of which is transversely angularly arched to 15 provide a recessed contour indicated by the numeral 16 which makes it substantially complementary to the upper surface of the ribbed sole 4; the concavity of said plate, however, having a less obtuse angle than the 20 convexity of said sole; and the plate having preferably the same horizontal outline as the sole. A flange 17 depends from the wider end of the plate and is provided with a horizontal opening 18 adapted for the reception 25 of the dowel 11 that projects from the fixed end of the bracket sole. A tapered lug 19 is provided depending from the plate 15 and adapted to seat in the socket of the sole, the lug having a truncate semi-globular concavity 20 positioned facing the flange 17 and with its axis in the inwardly extended axis of the opening 18.

Guide projections 21 comprising fingers are provided depending from the flange 17 35 and adapted for engagement with the pedestal, as a means of guiding the supporting member into position for reception of the dowel in the opening in the flange 17.

The supporting member 14 is preferably 40 a permanent part of a pressing board unit; the shaped pressing board member designed to carry a garment, or a part of a garment, to be pressed being designated as 22; and a plurality of such pressing board units comprising the garment carrying member and the supporting member, may be provided as 45 my device contemplates. The plate 15 of the supporting member is provided with screw threaded openings 23 disposed to coincide with openings 24 in the garment carrying member for the projection of screws 25, the heads and points of which are sunk, whereby a smooth under surface for the plate and a smooth upper surface for the 50 garment carrying member are preserved.

The supporting member 14 is provided with a boss 26 laterally extending from the wider end thereof and having an opening 27 for the accommodation of a loop 28 adapted to engage and secure an end of a cover 29 with 55 which the garment carrying member of the pressing board may be provided.

The parts so far described having been 60 provided, the pressing board unit, which, as stated, is one of a plurality of units having

different shaped garment carrying members, is attached to the bracket in the following manner:

The board is tilted, the flanged end of the supporting member depressed and guided into position by the projections 21 engaged over the rib, and the dowel is engaged in the opening of the flange. The remote end of the pressing board is then depressed, the lug depending from the plate entering the 70 socket of the sole and, by reason of the said lug's tapered shape, displacing the ball into the channel against the spring 10. The tapered lug, entering and proceeding through the tapered socket, bears against the walls 75 of the socket in opposition to the flanged end of the supporting member that is retained by the dowel and that bears against the end of the sole; the lug therefore acting as a lever to draw the supporting member longitudinally and into close contact with the sole. The ball rolling away from the 80 socket under the influence of the lug, is returned under the influence of the spring into normal position by its admission into the concavity 20 of the lug; the ball there serving to latch the lug and the plate in engagement with the sole. The substantially complementary contour of sole upper surface and 85 plate lower surface as mentioned enable the two to engage each other snugly; attention being called to the structure by which the outer edges of the two members are engaged, due to the greater concavity of the plate 90 compared with the convexity of the sole. The pressing board therefore is held in close contact to, and so is secure and stable in its connection with, the sole and the bracket.

When it is desired to remove the pressing board, for example, for substituting of a board of a different shape, the remote end of the pressing board is lifted, the influence being sufficient through the exercise of a slight force to extricate the lug from its engagement with the ball by displacing the ball into the channel; and as the pressing board is tilted, the flange is released from its engagement with the dowel. The provision of a ball as a latching element reduces the frictional wear connected with disengagement of the latch; and also reduces the burden involved, since the rolling of the ball facilitates the positioning of the lug which at such moment supports the board, in the 105 socket.

The bracket is, in the construction illustrated, fixed on a base 30 which may be of wood or iron. Internally screw threaded openings are provided indicated by 31 in the base plate of the bracket, and openings 32 in the base, screws 33 joining the two elements and being countersunk in the base enabling the base to present a smooth lower surface; and as shown, the screws projecting into the 110 base plate of the bracket approximately to 115

the thickness thereof so that a smooth surface is presented, whereby possible accidental damage to the garments being pressed is avoided.

5. What I claim and desire to secure by Letters Patent is:

1. In a device of the class described, a bracket comprising a supporting member having a rearwardly extending rib, a plate

10 integral with the upper end of the supporting member, an attaching member for seating on the plate, a pressing board secured to the attaching member, means for removably securing the attaching member to the plate

15 and means carried by the attaching member for engaging the rib for guiding the attaching member into seated position.

2. A pressing device comprising a bracket, a plate member on the bracket having an inwardly extending bore, a dowel mounted in said bore, a pressing board, and an attaching member secured to said pressing board and adapted to seat upon said plate member having a depending flange provided with an opening for the reception of said dowel and means for guiding the attaching member into relation with said bracket.

3. A device of the class described, comprising a support having a rearwardly extending dowel and a socket in its upper face, a pressing board, an attaching member secured to the pressing board adapted to be received upon the support, said member having a downwardly projecting flange provided with an opening for slidably mounting the flange upon the dowel and a lug adapted to be received in the socket, and means for latching the lug in the socket.

4. A device of the class described, comprising a support having a rearwardly extending dowel and a socket in its upper face, a pressing board, an attaching member on the pressing board adapted to be received upon

the support having a downwardly projecting flange provided with an opening for engaging the dowel and a lug having a recess adapted to be received in the socket, and a spring pressed ball mounted in the support in line with said lug for engaging in the recess in the lug.

5. A device of the class described, comprising a support having a rearwardly extending dowel and a socket in its upper face, a pressing board, an attaching member on the pressing board having a downwardly extending flange provided with an opening for engaging the dowel and a lug adapted to be received in the socket, means on the flange adapted to engage a portion of the support for positioning the attaching member on the support for engagement with the dowel, and means for latching the lug in the socket including said dowel.

6. In a device for use in pressing garments, a bracket comprising a support, a horizontal plate integral with the bracket, the plate having a cylindrical bore extending inwardly from its rear end and a vertical tapered opening adjacent the inner extremity of said bore and in communication therewith, a dowel fixed in said bore and projecting from the rear end thereof, the bore having a restricted inner opening, a ball in said bore having a portion extending into said opening, an expansion spring in said bore bearing against the dowel and the ball, and a pressing board comprising a shelf and a supporting member, the supporting member having means adapted to be engaged by said dowel, and a depending lug adapted to be received in the vertical opening in said plate, and having a recess adapted for engagement with said ball.

In testimony whereof I affix my signature.

ARO M. HARVEY.
